Application April 8, 1932, Serial No. 604,022,
and in Germany April 10, 1931

11 Claims. (Cl. 178—6)

In the use of Nipkow disc for television apparatus it is essential for the disc to run at the desired speed of rotation, which normally lies between 12 and 25 revolutions per second, steadily 5 in one plane without making either radial or axial movements. During running, therefore, there should be no irregularities such as are often produced by the stresses of the disc plate itself or by other causes. This requirement becomes all 10 the more difficult to fulfil, the greater the diameter of the disc, particularly when the latter is made of thin metal sheet, which however is necessary if the inertia is to be kept low.

It has been found by experiment that discs, 15 particularly discs of large diameter and high speed of rotation, run steadily if they are made in the form of a spoked wheel, or are "holed", meaning that between a boss portion and a rim portion parts of the material of the disc are removed by cutting holes of any desired shape. 20 Disadvantages occur, however; even with these discs because, due to slight and generally unavoidable strain caused during running by the resistance of the air, the thin spokes of such wheels 25 readily set themselves somewhat transversely, thereby producing fluttering of the disc and, above all, very unpleasant noises.

These defects are obviated according to the invention by the arrangement to be described 30 hereinafter. The essential feature of the invention resides in the provision on either side of the spoked wheel of solid discs of light material, for example thin sheet metal, presspahn, pertinax, cardboard or stout paper, having a radius smaller 35 than, equal to or larger than the radius of the spokes. These auxiliary discs are firmly clamped with the Nipkow disc on the spindle, but they are not otherwise connected to it at any point. Since the auxiliary discs are not rigid, they do not bear 40 against the Nipkow disc in the position of rest, but stand out far away from it. They only bear against the Nipkow disc during rotation and then only to an extent depending upon their resiliency and the centrifugal force or the currents of air 45 which are set up.

During rotation of this combination of discs, the air between the auxiliary discs is also set in rotation by friction against the auxiliary discs and at the same time it is forced outwardly. The 50 result of this is, in the first place, that the air between the two auxiliary discs moves in the same direction as the Nipkow disc, so that the spokes of the Nipkow disc are substantially at rest relatively to the air rotating with them. In the second place, however, due to the air being forced 55

outwardly and the partial vacuum produced thereby, the auxiliary discs bear against the Nipkow disc, thus preventing the three discs from gaping apart at the edge. It has been found by experience that it is occasionally preferable 60 to insert between the auxiliary discs and the Nipkow disc small distance discs of slight thickness made of resilient material, for example rubber, thereby forming a certain air space round the Nipkow disc. The air space formed during rotation, however, should not be too large in the axial direction. The effect desired according to the invention is best obtained when the said air space is quite small, for instance of the order 65 of the magnitude of the thickness of the sheet metal 70 of the Nipkow disc.

If distance rings are not inserted between the auxiliary discs and Nipkow disc, the auxiliary discs, particularly when they are made of very thin material, for example paper, bear too hard 75 against the Nipkow disc, due to the reduced air pressure, and the disadvantages of a solid disc readily make their appearance (for example, the disc starts to wobble), which is just what the cut-out portions are intended to obviate. It is now 80 possible to obviate this disadvantage by the insertion of the intermediate discs without thereby impairing the advantages of the auxiliary discs.

In brief, the essential feature of the invention does not consist of, say, firmly clamping the Nipkow disc by or with the two auxiliary discs, as in clamping circular saws, polishing wheels, grindstones, etc., but of forming an air space round the portion of the Nipkow disc which is not employed 85 for picture scanning or composing, the relative 90 velocity of the said air space being very small in comparison with the rotating Nipkow disc.

Of course, the principle of the invention is not limited to holed discs, but it also provides certain 95 improvements in the case of solid discs, since the bulges or other irregularities of the discs do not then have such a considerable effect.

Figure 1 of the accompanying drawing shows in section a disc arrangement based on the principle of the invention, and

Figure 2 the same arrangement in elevation.

The holed Nipkow disc 1 with the spokes 2, 2', 2'', etc. is secured together with the two solid auxiliary discs 3 and 4 and the distance discs 5 and 6 on the hub 7 by means of the nut 8. The hub with the discs firmly clamped on it is, in its turn, fixed to the shaft 9 by known methods.

Having now particularly described and ascertained the nature of our said invention and in

what manner the same is to be performed, we declare that what we claim is:—

1. In a television system, a Nipkow-disc and an auxiliary disc of smaller diameter on each side thereof in axially spaced relation to form a relatively narrow air space between said Nipkow-disc and each auxiliary disc. 5
2. In a television system, a Nipkow-disc and an auxiliary disc of smaller diameter on each side thereof adapted to rotate with the same speed as said Nipkow-disc, said auxiliary discs being axially spaced from said Nipkow-disc to form a narrow air space therebetween. 10
3. In a television system, a Nipkow-disc and an auxiliary disc of smaller diameter on each side thereof in axially spaced relation to form a narrow air space between said Nipkow-disc and each auxiliary disc, said auxiliary discs being formed of thin resilient material and being adapted to 15 bear against the sides of said Nipkow-disc during the rotation thereof.
4. In a television system, a Nipkow-disc and an auxiliary disc of smaller diameter on each side thereof adapted to rotate with the same speed as said Nipkow-disc, said auxiliary discs being axially spaced from said Nipkow-disc to form a narrow air space therebetween, said auxiliary discs being formed of thin resilient material and being adapted to bear against the sides of said 20 Nipkow-disc during the rotation thereof. 30
5. In combination with a Nipkow-disc provided with apertures to form spokes in the body of said disc, two solid auxiliary discs, one on each side of said Nipkow-disc and axially spaced therefrom to form a narrow air space between said Nipkow-disc and each of said auxiliary discs, said auxiliary discs having a smaller diameter than said Nipkow-disc and adapted to cover the spokes formed in the body of said Nipkow-disc. 35
6. In combination with a Nipkow-disc provided with apertures to form spokes in the body of said disc, two solid auxiliary discs, one on each side of said Nipkow-disc and axially spaced therefrom to form a narrow air space between said Nipkow-disc and each of said auxiliary discs, said auxil- 40

iary discs being of a diameter to cover the spokes formed in the body of said Nipkow-disc, said auxiliary discs being formed of thin resilient material and being adapted to bear against the sides of said Nipkow-disc during the rotation thereof. 80

7. In a television system, a Nipkow-disc having on each side a solid auxiliary disc of smaller diameter, means for forming a narrow air space between said Nipkow-disc and said auxiliary discs, and means for clamping said Nipkow-disc, air space forming means and auxiliary discs firmly together to permit simultaneous rotation of said Nipkow-disc and auxiliary discs. 85

8. In combination, a Nipkow-disc and solid auxiliary discs of smaller diameter, one on each side thereof, means between the center portions of said discs for forming a narrow air space therebetween, and means for securing said discs together to permit simultaneous rotation of the same. 90

9. In combination with a Nipkow-disc on a rotatable shaft, two solid auxiliary discs which are fixedly secured to said shaft adjacent opposite sides of said Nipkow-disc and being axially spaced therefrom to form a narrow air space between 100 said Nipkow-disc and each auxiliary disc.

10. In combination with a Nipkow-disc on a rotatable shaft, two solid auxiliary discs of smaller diameter, and means on said shaft and positioned between said Nipkow-disc and each auxiliary disc for forming a narrow air space between 105 said discs.

11. In combination with a Nipkow-disc on a rotatable shaft, two solid auxiliary discs of smaller diameter, and means on said shaft and positioned between said Nipkow-disc and each auxiliary disc for forming a narrow air space between 110 said discs, said auxiliary discs being fixedly secured on said shaft and being formed of thin resilient material and being adapted to bear 115 against the sides of said Nipkow-disc during the rotation thereof.
